UNITED STATES PATENT OFFICE.

HAROLD H. FEBREY, OF NEWARK, NEW JERSEY, ASSIGNOR TO THE AMERICAN STEEL AND WIRE COMPANY OF NEW JERSEY, A CORPORATION OF NEW JERSEY.

RAIL BOND AND METHOD OF MAKING SAME.

Application filed September 3, 1921. Serial No. 498,313.

To all whom it may concern:

Be it known that I, HAROLD H. FEBREY, a citizen of the United States, and resident of Newark, in the county of Essex and State of New Jersey, have invented certain new and useful Improvements in Rail Bonds and Methods of Making Same, of which the following is a specification.

This invention relates to rail bonds, and 10 while not limited thereto, more particularly relates to the manufacture of rail bonds having rigid terminals, formed of two dissimilar metals, on the ends of a flexible conductor, with the terminals permanently united to the 15 ends of the conductor by a fusing or welding operation.

One object of my invention is the provision of an improved method of making rail bonds whereby the parts of the rail bond are 20 secured one to another in providing the molten metal used to form the body portion of the rail bond terminals, and whereby the difficulties heretofore experienced in uniting or welding two dissimilar metals or 25 metals differing in composition or electrical conductivity, such as steel and copper, are avoided and overcome.

Another object of my invention is the provision of a rail bond which is particularly 30 adapted for use in applying rail bonds to a track rail by what is known as the metallic electrode arc welding process.

Another object of the invention is the provision in a rail bond of a conductor and terminals formed of cuprous or similar relatively soft metal and a rail engaging face on the cuprous terminals formed of ferrous or similar relatively hard metal.

A further object of this invention is to 40 provide a rail bond having terminals of composite construction which are constructed with edges of restricted area to contact with the track rails prior to welding the bond terminals to the rails, so as to expose a maximum area of rail surface opposite the bond terminals for engagement by the contact metal employed in securing the rail bonds to the track rails.

Still further objects of my invention consist in the provision of rail bonds having 50 the novel constructions, arrangements, and combination of parts shown in the drawings, to be described in detail hereinafter, and to be particularly pointed out in the appended claims.

Referring now to the drawings, forming part of this specification, Figure 1 is an end elevation showing a track rail, with one form of rail bond, (of T-head type), embodying my invention, as applied for use 60 to the heads of the track rails. Figure 2 is a side elevation showing details in the construction of the rail bond of Figure 1. Figure 3 is a plan, and Figure 4 is an end elevation showing details in the construction of the ends of the conductor of the rail bond of Figures 1 and 2, as formed 65 prior to attaching the rail bond terminals thereto.

Figure 5 is a plan showing a preferred 70 form of recessed mold used in fabricating the bond terminals and in uniting the parts of the bond terminals to each other and to the conductor ends, in accordance with the method forming part of this invention. Figure 6 is a sectional side elevation, on the line 75 VI—VI of Figure 5, showing further details in the construction of the mold of Figure 5, and the manner of supplying molten metal to the mold cavity in forming the bond terminals.

Figure 7 is a side elevation, partly in section, showing the rail bond conductor, with a terminal as built-up thereon in the mold of Figures 5 and 6, and Figure 8 is a sectional side elevation showing one arrangement of drop forging dies adapted for use 85 in drop forging the rail bond terminals of Figure 7, to compact the metal in the bond terminals and finish the terminals to the 90 desired shape and size.

Figure 9 is an end elevation showing a track rail, with a modified form of rail bond, (a long terminal single strand rail bond), constructed in accordance with this invention, as secured to the web of the track rail. Figure 10 is a perspective plan showing details in the construction of the terminals of the rail bond of Figure 9. Figure 11 is a plan, and Figure 12 is a sectional end elevation, showing one form of recessed mold adapted for use in fabricating or building up 100 the rail bond terminals of Figures 9 and 10, in accordance with my invention.

Figure 13 is an end elevation showing another modified form of rail bond, made in accordance with my invention, as secured to a track rail. Figure 14 is a side elevation showing details in the construction of the rail bond of Figure 13. Figure 15 is a 110

plan showing one form of recessed mold adapted for use in forming the terminals of rail bonds like that shown in Figure 14, according to the method forming part of my invention.

Figure 16 is an end elevation showing a rail having another modified form of rail bond attached thereto, which embodies my invention and is made in accordance with 10 the method forming part of the invention. Figure 17 is a side elevation showing details in the construction of the rail bond of Figure 16. Figure 18 is a plan showing the construction of the rail bond terminal of 15 the bond of Figures 16 and 17, as molded in accordance with my improved invention, and attached to the bond conductor preparatory to being drop forged to finished shape and size. Figure 19 is an end elevation, 20 partly in section, of the rail bond terminal shown in Figure 18. Figure 20 is a sectional end elevation showing details in the construction of the recessed mold used in fabricating the rail bond terminal of Figures 18 and 19.

In Figures 1 to 4 of the accompanying drawings, the numeral 2 designates the head of a track rail having the bond terminals secured thereto. The rail bond shown there- 30 in comprises a flexible double strand conductor, 3 having a ferrule or sleeve 4, made of copper or like material, on the ends thereof. This ferrule 4 is used to temporarily secure together the ends of the strands forming the conductor, (see Figures 3 and 4), the sleeve later becoming fused and thereby merged with the body of the terminal 5 and end of the conductor 3. The terminal is provided with a rail contacting face 6, 40 which is formed of a strip of steel or similar relatively hard ferrous metal approximating the electrical conductivity of the rail head 2.

As shown in Figure 1 the hard metal contact face 6 of the terminal is concave and has a bottom edge 7, which is adapted to engage the side surface of the rail head 2 so as to form a pocket having a relatively wide bottom, the result of shaping the pocket in 50 this way being to facilitate the introduction and manipulation of the electrode used in welding, or supplying the metal 8 used in welding the face of the rail bond terminal to the rail and to increase the area of the 55 rail surface in contact with the attaching metal 8. It will of course be understood that when desired, the rail contacting face 6 of the terminals will be flat, as in Figure 16, instead of curved in the manner shown 60 in Figure 1.

In making rail bonds like that shown in Figures 1 and 2, a mold 10, made of carbon, is employed, (although a metal mold may be used), this mold having a recess or cavity 11 in the upper face thereof, of suitable

size and shape. One end of the bond conductors 3, which is provided with a ferrule or sleeve 4, (see Figures 3 and 4), is then placed within the mold cavity 11 and a short flat piece 6, of steel or other relatively hard metal is also positioned within the mold cavity, as is shown in Figures 5 and 6; this plate 6 forming a hard metal face on the finished bond terminal.

The conductor 3 and, through the me- 70 dium of the mold 10, the plate 6 form one pole of an electric circuit, the other pole preferably being formed of a non-metallic electrode 12. An electric arc being established between the plate 6 and end of the 75 conductor 3, forming one terminal, and the non-metallic electrode 12 forming the other terminal, the adjoining surfaces of the end of the conductor 3 and plate 6 will become heated and fused. A metal rod or pencil of 80 suitable composition is then introduced into the electric arc and is fused thereby, the fused metal dropping into and gradually filling the mold cavity 11 and being united 85 with or welded to the fused surfaces of the 90 end of the conductor 3 and the plate 6.

By filling the mold cavity 11 in this manner, a terminal having a body portion 5 and a hard metal face 6 with a rearwardly extending projection 4, is built up or formed, 95 the terminal made in this way being illustrated in Figure 7. The metal forming the body portion 5 of the terminal when made in this way is liable to be more or less porous and relatively weak mechanically, and 100 on account of its rough appearance will appear unfinished, although in a condition for use.

The so formed terminal after being removed from its mold and cleaned, is heated, 105 in the reducing flame of an oil or other suitable furnace, to a forging temperature, or temperature necessary to give the desired plasticity to the metal of the terminal. The heated terminal is then drop forged within 110 the cavity 13 of the top and bottom forging dies 14 and 15, (see Figure 8), and in this drop forging operation the relatively soft metal forming the body portion thereof is made more dense and homogeneous, so as to increase the strength and conductivity of 115 the terminal, while it also is shaped to size and contour and given a uniform and finished appearance. The outer surface of the plate 6 of the rail bond terminal may be 120 made concave in this operation, as shown in Figure 1, or it may be made flat when desired. The shape of the cavities in the drop forging dies will be made of the contour 125 desired.

At the completion of the drop forging operation, the rail bond terminals will be trimmed, to remove the flash or fin produced thereon in drop forging, and when the steps 130 as described above are repeated with the

other terminal of the rail bond, a completed article is made.

The modified form of rail bond shown in Figures 9 and 10 embodies the same general features as the bond of Figures 1 and 2, which has been described, except that in the long terminal bond of Figures 9 and 10, the hard metal rail engaging face 6^a of the bond terminals 5^a is not concave and the conductor 3^a is shown attached to the end of the terminals 5^a (instead of to one side of the terminal, as in Figures 1 and 2). The rail bond of Figures 9 and 10 is adapted to be welded either to the flange or to the web of the track rail in bonding the rails, Figure 9 showing it secured to the rail web by means of the attaching metal 8^a. Like parts in the rail bond of Figures 9 and 10 have the same numerals as in Figures 1 and 2, with the exponent "a" added thereto.

The terminals on the bonds of Figures 9 and 10 will be built up or fabricated and afterward drop forged in the same manner as has been described in connection with the rail bond of Figures 1 and 2. The end of the conductor 3^a will be provided with a sleeve 4^a and steel face 6^a and the body portion 5^a of the terminal will be built up in a suitably shaped cavity 11^a in the mold 10^a, (see Figures 11 and 12).

In the construction illustrated in Figures 13 and 14, a rail bond is shown having L-shaped terminals 5^b and a flexible double strand conductor 3^b which is adapted to be applied for use between the adjacent faces of a splice bar and the web of the rails 2^b connected together by the splice bar. The inner faces 6^b of the L-shaped terminals of this bond are set at an angle so as to form an outwardly flaring surface to engage with the metal 8^b used in securing the rail bond to the web of the track rails 2^b. In molding or forming the terminals of the rail bond of Figures 13 and 14 right and left hand molds, constructed as shown in Figure 15, will be employed. These molds 10^b will have a suitable shaped cavity 11^b therein and an L-shaped steel or other relatively hard metal face 6^b will be inserted in the mold together with the end of the bond conductor 3^b in the manner shown in Figure 15, and the metal added thereto in order to build up the body of the terminal will be supplied in the manner hereinbefore described in connection with the rail bond of Figures 1 and 2.

The double strand bond of Figures 13 and 14 will be built up, in a mold like that shown in Figure 15, in the same way as hereinbefore described. The ends of the strands forming the conductor 3^b will be provided with sleeves 4^b and the ends of the strands will be positioned within the cavity 11^b of the mold 10^b, together with a bent strip 6^b of hard metal and the body 5^b of the L-shaped terminal will then be built up and

welded to the terminal and strip 6^b by fused metal from a suitable rod or pencil. The so formed terminal will then be drop forged to size and finished shape.

In the rail bond illustrated in Figures 16 and 17, 18, 19 and 20 (in which like parts have the same numerals applied thereto as in Figures 1 and 2, with the exponent "c" added), the ferrule or sleeve 4^c, to which the end of the flexible conductor 3^c is secured, is formed by welding a short solid copper plug 4^c to the body 5^c of the terminal and at the same time the hard metal rail engaging face 6^c is attached to the body of the terminal. The metal forming the body 5^c of the terminal will be fused and added to the mold 10^c in the same manner as has been described heretofore and after the terminals have been formed in the mold 10^c in the manner shown in Figure 18, the plugs 4^c are drilled to form a socket into which the end of the single strand terminal 3^c is inserted. The terminal is then formed and put on the other end of the conductor 3^c. The terminals and connected ends of the bond conductor 3^c are then heated and drop forged, this operation uniting the terminals to the conductor and shaping the terminals to size and the contour shown in Figures 17 and 18.

The many advantages of this invention will be apparent to those skilled in the art. Special attention is directed to the feature of having the terminals provided with only one steel face, thus allowing the forging of the copper body.

Steel and copper will not flow equally in the dies when at an equal temperature, due to the difference in plasticity of these metals. However, when arranged as herein shown and described, with a steel face on but one side of the terminal, the steel will retain approximately its original position, while the movement of the excess metal in the body of the terminal occurs in the forging operation.

It will, of course, be understood that while the drawings and specification show and describe rail bonds having both single and double strands forming the flexible conductor, any number of conductors, either flexible or rigid may be used as desired. It will also be understood that while I have described and shown certain forms of terminals with great particularity, that I do not wish to be limited to these exact forms since terminals of various shapes may readily be used, and different materials may be utilized in forming them.

Various other modifications may be made, as will be apparent to those skilled in the art, without departing from the spirit of my invention as defined in the appended claims.

I claim:—

1. In the manufacture of rail bonds, the

steps consisting in securing a part of the bond terminal and the end of the bond conductor within the cavity of a mold, and then adding molten metal to the mold cavity to thereby form the body of said terminal and unite said terminal part and conductor end to said terminal body.

2. In the manufacture of rail bonds, the steps consisting in securing a part of the bond terminal and the end of the bond conductor within the cavity of a mold, heating the parts of the rail bond in said mold cavity, and then adding molten metal to the mold cavity to thereby form the body of said terminal and unite said terminal part and conductor end to said terminal body.

3. In the manufacture of rail bonds, the steps consisting in securing a part of the bond terminal and the end of the bond conductor within the cavity of a mold, and then adding molten metal to the mold cavity to thereby form the body of said terminal and unite said terminal part and conductor end to said terminal body, and then heating and drop forging the terminal to size and finished shape.

4. In the manufacture of rail bonds, the steps consisting in securing a part of the bond terminal and the end of the bond conductor within the cavity of a mold, heating the parts of the rail bond in said mold cavity, and then adding molten metal to the mold cavity to thereby form the body of said terminal and unite said terminal part and conductor end to said terminal body, and then heating and drop forging the terminal to size and finished shape.

5. The method of making rail bonds which consists in positioning the end of a metallic conductor in a mold, positioning a strip of harder metal in the mold in spaced relation to said conductor end, filling the intervening space with molten metal and thereby forming a terminal united to said conductor end and having a contacting face of relatively hard metal, and then heating and drop forging the so formed terminal to size and shape.

6. The method of making rail bonds which consists in positioning the end of a metallic conductor and a strip of harder and dissimilar metal within a mold with the metal strip in spaced relation to said conductor, fusing the adjacent surfaces of said

conductor end and said metal strip, filling 55 the intervening space with molten metal and thereby forming a terminal body having a contacting face of relatively hard metal and united to said conductor, and then heating and drop forging the so formed terminal to 60 compact and shape the metal of said terminal in said forging step to final contour and size.

7. The method of making rail bonds which consists in positioning the end of the bond 65 conductor in a mold cavity, positioning a strip of relatively harder metal in said mold cavity in spaced relation to said conductor end, forming an electric arc between said conductor end, said plate and an electrode 70 and thereby fusing the adjacent surfaces of said conductor end and said plate, introducing a metal pencil into said arc, and thereby fusing the pencil and filling the space in said mold cavity with molten metal 75 to unite said adjacent fused surfaces and mold the terminal to shape, and then heating and drop forging said molded terminal to shape and size.

8. The method of making rail bonds 80 which consists in binding the ends of a bond conductor, shaping a terminal of relatively soft metal on each end of said conductor within a mold, securing a rail contacting face of relatively hard metal to said terminals in molding the terminals, and then heating and forging the so formed terminals to further shape the terminals and complete the rail bond.

9. The method of making rail bonds 90 which consists in molding a terminal on the end of a flexible conductor, said terminal and conductor being relatively soft metal, securing a contacting face of relatively hard metal to said terminal in the terminal molding operation, and heating and forging the completed terminals to size and shape.

10. A rail bond comprising a conductor having forged terminals on the ends thereof, said terminals having concave rail engaging faces coacting with the rail to form a pocket therebetween, and said rail engaging faces and the body of said terminals being of dissimilar metals.

In testimony whereof I have hereunto set 105 my hand.

HAROLD H. FEBREY.
